UNITED STATES PATENT OFFICE

1,980,863

CONDIMENT HOLDER

John Oliver Clifton Ingold, Havana, Kans.

Application July 11, 1934, Serial No. 734,659

3 Claims. (Cl. 65—45)

The invention relates to condiment holders and particularly to combined salt and pepper shakers, and has for its object to provide a device of this character having separate independent chambers formed by a partition between the chambers and a cover having discharge apertures registering with the chambers and hinged closures hinged adjacent the outer opposite edges of the cover and adapted to close against the inner face of the cover and close the apertures therein when material is being discharged from the lower chamber through its registering apertures in the cover.

A further object is to hingedly connect the closures on the cover in a position whereby when the salt cellar is inverted and placed at an incline, one of said closures will hinge downwardly to open position against the inner wall of the cellar body and the other closure to hinge downwardly and outwardly into cooperative closed position with the cover apertures.

A further object is to provide a transverse rib on the inner wall of the cellar body and adapted to extend above a free edge or end of the closures when in down open position whereby material will not pass under the closure and prevent the same from closing, said ribs directing material to the top of the closure on the initial movement of the condiment holder to inverted inclined position.

A further object is to form the cover from a disc on which the closures are mounted adjacent opposite edges so they will be disposed adjacent the inner walls of the body of the holder and to provide a channelled member, one flange of which engages the outer side of the neck of the cellar body and the other overlies the perforated disc, thereby allowing the device to be easily disassembled and the disc to be easily cleaned.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of the cellar.
Figure 2 is a vertical longitudinal sectional view through the cellar.

Figure 3 is a vertical longitudinal sectional view through the cover end of the cellar, showing the same in an inverted inclined position.

Figure 4 is a bottom perspective of the disc and hinged covers carried thereby.

Referring to the drawing, the numeral 1 designates the body of the combination salt and pepper shaker, 2 the salt compartment therein, 3 the pepper compartment. Compartments 2 and 3 are formed by a wall or partition 4 which extends through the body 1 and is preferably formed integral therewith. The shaker may be cast from a single piece of glass or other material, or may be formed from tin if desired. The particular form shown is for purposes of illustration.

Disposed on the upper end of the body 1 is a perforated disc 5, which is preferably rectangular shaped as shown, and is provided with salt discharge apertures 6, which register with the salt chamber 2 and pepper discharge apertures 7 which register with the chamber 3, and as the upper end of the partition 4 engages the under side of the disc 5 at 8, it will be seen that when the cellar as a whole is placed in an inverted inclined position as shown in Figure 3, the contents of either compartment may be discharged therefrom, however through the mechanism hereinafter set forth only the contents of the lower compartment can be discharged when the device is inverted.

The perforated disc 5 is held in position on the open end of the body 1 by means of a rectangularly shaped member 9, angularly shaped in cross section and the flange 10 of which interengages at 11 with the outer side of the neck of the body for holding the member 9 in position. The flange 12 of the member 9 engages the outer side of the disc and retains the disc in position on the neck of the body 1. By this particular construction the disc can be removed from the body and may be thoroughly cleaned which would not be the case if the disc were formed integral with the member 9.

Extending downwardly from the under side of the perforated disc 5 are spaced ears 13 in which the pintles 14 of the hinged closure 16 are mounted. It will be noted that the ears 13 are positioned where they will engage the inner side or wall of the body 1, thereby allowing the disc to be properly centered and positioned on the body 1 for holding the same until the rectangular shaped member 9 is in position. It will be seen that the hinged member 15, which is in down position will swing downwardly to open position as shown in Figure 3 when the cellar is in use and the other closure 15 will be in closed position, thereby allowing the contents of only the lower compartment to be discharged. To prevent salt or pep-

per from getting under the free end of closure 15 as shown in Figure 3, the inner wall of the compartments are provided with inwardly extending ribs or flanges 16 which will direct the 5 condiment to the upper side of the downwardly disposed closure, thereby insuring a positive operation of the device.

From the above it will be seen that a multiple chamber condiment holder is provided which is 10 simple in construction, one wherein the disc 5, carrying the closures 15 is separate from the rest of the cover, thereby allowing the same to be easily disassembled and cleaned, and the closures 15 will hinge inwardly and outwardly into 15 engagement with the wall of the body 1 and with their free ends behind ribs 16 for insuring a positive operation of the device.

The invention having been set forth what is claimed as new and useful is:

- 20 1. A combined salt and pepper shaker comprising a body member having adjacent chambers discharging through an open end of the body member, inner and outer walls carried by said chambers, a perforated cover mounted on the 25 open end of said body member and having discharge perforations registering with the chambers, hinged closures carried by the cover and hinged thereto adjacent the outer sides thereof and within the chambers, said closures being 30 hingedly connected to the cover in positions whereby when the shaker is placed in an inverted inclined position one of said closures will swing inwardly and downwardly into engagement with the outer wall of the lowered chamber and the 35 other closure will hinge downwardly and outwardly into engagement with the cover closing the perforations therein, and transverse ribs carried by the inside of the outer walls of the condiment chambers and extending beyond the free 40 ends of the hinged closures when in down position and forming means whereby material within the chambers when the device is inverted will be deflected to a position above the hinged closure which is in lowered or open position.
- 45 2. A combined salt and pepper shaker comprising a body member having adjacent chambers discharging through an open end of the body member, inner and outer walls carried by said

chambers, a perforated cover mounted on the open end of said body member and having discharge perforations registering with the chambers, hinged closures carried by the cover and hinged thereto adjacent the outer sides thereof and within the chambers, said closures being hingedly connected to the cover in positions whereby when the shaker is placed in an inverted inclined position one of said closures will swing inwardly and downwardly into engagement with the outer wall of the lowered chamber and the other closure will hinge downwardly and outwardly into engagement with the cover closing the perforations therein, said cover comprising a foraminous disc to which the hinged closures are connected, said disc engaging the discharge end of the body and the inside of the cover, and said cover further comprises a flanged member surrounding the discharge end of the body member and having a flange overlying the outer side of the disc.

3. A combined salt and pepper shaker comprising a body member having adjacent chambers discharging through an open end of the body member, inner and outer walls carried by said chambers, a perforated cover mounted on the open end of said body member and having discharge perforations registering with the chambers, hinged closures carried by the cover and hinged thereto adjacent the outer sides thereof and within the chambers, said closures being hingedly connected to the cover in positions whereby when the shaker is placed in an inverted inclined position one of said closures will swing inwardly and downwardly into engagement with the outer wall of the lowered chamber and the other closure will hinge downwardly and outwardly into engagement with the cover closing the perforations therein, said cover comprising a foraminous disc engaging the discharge end of the body member, 115 pairs of hinged lugs engaging the inner outer walls of the chambers and between which the hinged closures are mounted and a member angularly shaped in cross section surrounding the discharge end of the body of the cellar and overlying the outer side of the disc.
